UNITED STATES PATENT OFFICE.

JOHN C. HUB, OF LAKewood, OHIO.

FILING DEVICE.

1,109,631.

Specification of Letters Patent. Patented Sept. 1, 1914.

Application filed May 17, 1913. Serial No. 768,254.

To all whom it may concern:

Be it known that I, JOHN C. HUB, a citizen of the United States, and a resident of Lakewood, county of Cuyahoga, and State of Ohio, have invented a new and useful Improvement in Filing Devices, of which the following is a specification, the principle of the invention being herein explained and the best mode in which I have contemplated applying that principle, so as to distinguish it from other inventions.

In comprehensive filing systems, especially for filing correspondence where the volume of correspondence is large, it is necessary for obvious reasons to carefully keep track of any correspondence taken out of the files. As ordinarily carried out, a more or less elaborate charge system is employed for this purpose, the party, who desires to temporarily use any particular correspondence, having to write out an order which is duly entered before the file in question is turned over to him, and frequently other records are kept.

The object of the present invention is to provide a simple and convenient device whereby, not only may the charge be properly and automatically entered, but an indication left in the file itself of the location of the papers temporarily withdrawn, so that, should some one subsequently be looking for said papers, he will be at once advised as to their whereabouts.

To the accomplishment of the foregoing and related objects, said invention, then, consists of the means hereinafter fully described and particularly pointed out in the claims.

The annexed drawing and the following description set forth in detail certain mechanism embodying the invention, such disclosed means constituting, however, but one of the various mechanical forms in which the principle of the invention may be used.

In said annexed drawings:—Figure 1 is an elevational view of a guide which forms a principal element of the present improved device; Fig. 2 is a similar view of a portion of such guide showing a record slip designed to be used in conjunction therewith; Fig. 3 is an enlarged view of such record slip by itself; and Fig. 4 is a transverse sectional view of the slip in place on the guide, the plane of the section being indicated by the line 4—4, Fig. 2.

The guide 1, in its general form, is similar to those currently used for various systems

of card indexing, being provided with a tab 2 extending above its upper edge a suitable distance and located at a point transversely of the card, such as may be found most convenient in the particular installation. On such tab is printed in large characters the notation "Out", while below one portion of, and immediately adjacent to, the tab and the word printed thereon, are provided holding means adapted to receive a card, or slip, and hold the same with its upper edge aligned with that of said tab. Where the guide, as is preferable, is made out of thin sheet metal, the aforesaid holding means are conveniently provided by simply stamping up and bending inwardly three tongues 3, as shown in Figs. 1 and 2, enough space being left between the tongues and the surface of the guide to permit of the introduction of the record slip 4, as shown in Fig. 4. Such record slip 4 may take on various forms, but in any event should include a space 5, so located as to align with the word "Out", when the slip is in place on the guide, such space being designed to receive the name of the file withdrawn. Below such space, another space 6 for the address may be provided, as well as for various memoranda, and finally a space 7 for either the number, or the name, of the party making the withdrawal.

In using the foregoing improved filing device, it is merely necessary for a party who desires to withdraw a file, to enter the name, or name and address, of the correspondence desired on a slip 4, such as shown in Fig. 3, signing the slip in order that he may be properly charged. The filing clerk who receives the slip is enabled thereby to identify at once the correspondence desired, and upon withdrawing the same substitutes in its place one of the guides 1, such as shown in Fig. 1, first introducing the signed slip 4. When in place, the latter, as shown in Fig. 2, clearly indicates, to any subsequent searcher, what correspondence is "Out", at a glance. At the same time, by lifting the guide or tilting it back, the party holding the correspondence temporarily is disclosed. The convenience and simplicity of the device when thus used are thought to be sufficiently obvious not to require detailed explanation. It will be understood, of course, that when the correspondence is returned the guide is removed and the slip either destroyed or filed for the purpose of a permanent record.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

- 10 1. In a device of the character described, the combination with a guide provided with a projecting tab and a holder adjacent thereto; of a slip adapted to be inserted in such holder.
- 15 2. In a device of the character described, the combination with a guide provided with a projecting tab and a holder adjacent thereto, such tab bearing a notation; of a slip adapted to be inserted in such holder and having a space adapted to aline with the notation on such tab.
- 20 3. In a device of the character described, the combination with a guide provided with a projecting tab and a holder located below

one portion of such tab, such tab bearing 25 the notation "Out"; of a slip adapted to be inserted in such holder and having a space adapted to aline with the notation on such tab.

4. In an index, an out-card adapted to 30 be inserted into the index in place of withdrawn indexed matter, and a card adapted to display memoranda relative to such withdrawn matter and means for removably holding said card on the out-card.

5. In an index, an out-card adapted to be inserted into the index in place of withdrawn indexed matter, and a card adapted to display memoranda relative to such withdrawn matter; and a plurality of suitably 40 disposed tongues mounted on said out-card and adapted to removably hold said card.

Signed by me, this 15th day of May, 1913.

JOHN C. HUB.
